Inventor,
Ernest J. Shaffer,
Attys.

UNITED STATES PATENT OFFICE.

ERNEST J. SHAFFER, OF TULSA, OKLAHOMA.

SUCKER-ROD SLIP SOCKET.

Application filed December 24, 1921. Serial No. 524,689.

To all whom it may concern:

Be it known that I, ERNEST J. SHAFFER, a citizen of the United States, residing at Tulsa, in the county of Tulsa and State of Oklahoma, have invented a certain new and useful Improvement in Sucker-Rod Slip Sockets, of which the following is a full, clear, and exact description, reference being had to the accompanying drawings.

10 This invention relates generally to equipment used in deep well operations, and has to do more particularly with a slip socket for recovering broken sucker rods from well tubing where the break occurs in the body 15 portion of the rod—that is, somewhere intermediate the enlarged ends where the rod is coupled to adjoining rods of the string.

I have already contributed to the art, improvements in slip sockets for catching not only breaks in the body portions of the rods but breaks occurring at the welds and 20 couplings. Sockets having this wider range of adaptability are exhibited in my copending applications, Serial Nos. 291,799 and 25 426,974, filed respectively on the 22nd day of April 1919, and on the 29th day of November, 1920. While these more elaborate and consequently more expensive devices are indispensable in deep well operations, nevertheless, inasmuch as the great 30 majority of breaks occur in the body portions of the rods, a simple and inexpensive slip socket for catching only such breaks has a very extensive field of utility and is 35 much in demand.

The objects of my present invention, therefore, are to provide a simple, durable, inexpensive, yet highly efficient slip socket for catching breaks in sucker rods, and which 40 is so constructed as to automatically assume a hold upon the sucker rod when presented in operative relation thereto and which hold becomes more secure as the socket is retracted and the string of sucker rods lifted, yet 45 which may be very easily disengaged from the rod when removed from the tubing; and which is practically indestructible and free from disorder; which is very convenient of use; and wherein the slip, while having perfect 50 freedom of reciprocation, so interlocks with the barrel or casing as to be held positively against dislodgment therefrom.

An embodiment of the invention wherein the foregoing objects are attained is illustrated in the accompanying drawing. Fig. 55 1 is an elevational view of my improved

slip socket; Fig. 2 is a section on the line 2—2 of Fig. 1; and Fig. 3 is a central vertical section through the socket, indicating the position of the device in a well tubing, suspended from a string of sucker rods, and grasping a broken rod, by including these 60 associated parts in dot-and-dash lines.

The socket comprises a cylindrical barrel 1 that is internally threaded at its upper end and is reduced slightly in internal diameter adjacent its lower end to provide a shoulder 2. The lip 3 surrounding the mouth of the barrel is inclined upwardly and inwardly at a slight angle for a purpose 70 which shall presently appear.

A cap 5 is applied to the upper end of the barrel by having its externally threaded reduced lower end screwed into threaded portion of the barrel. The cap is provided with a wrench-receiving portion 6 and a threaded pin 7. A bore 8 leads upwardly through the cap from the interior of the barrel and out through one side of the portion 6. Set within opposite sides of the barrel 1 are a 80 fixed jaw 10 and a guide plate 11 that are substantially semi-cylindrical in form so as to fit the barrel. These parts are held in place by screws 12, and to relieve the screws of any shearing action due to an end thrust 85 upon the parts, particularly as when a string of rods is being lifted, the jaw 10 and guide plate 11 fit between the cap 5 and the shoulder 2 of the barrel 1, the jaw and guide plate having complementary shoulders 10^a and 11^a, respectively engaging said shoulder of the barrel. The lower ends of the jaw and guide plate incline upwardly and inwardly in the plane of the lip 3 of 90 the barrel.

The inner surface of the plate 11 is shown as straight for a suitable distance downwardly from its upward end, and continuing therefrom to the lower end of the plate said surface is inclined inwardly at a slight angle, said inclined portion being designated 13. Arranged for cooperation with the inclined portion 13 is a slip 15 having its outer surface tapered to correspond to the angular inclination of the said portion 13. The slip is held against dislodgement by a stud 16 that projects through a slot 17 in the plate 11 and has an enlarged head 18 that is adapted to travel within a wider slot 19 of the barrel. At its extreme upper end, the slot 17 is made wide enough to pass the head 18 to enable the placing of the slip 100 105 110

within the socket and its removal therefrom. However, unless the cap 5 is unscrewed somewhat to permit sufficient elevation of the slip 15 to bring the pin 16 entirely within the widened upper end of the slot 17, the head 18 cannot be passed through such widened portion. Accordingly, when the device is in operative condition, the slip 15 cannot be disengaged from the socket.

10 In considering the operation of the device, it may be assumed that a sucker rod A has been broken within the well tubing B. My improved socket is then applied to the end of a string of sucker rods, represented at 15 C, by screwing its pin 7 into the coupling D of the lower rod of the string. It is then lowered by means of said string into the well tubing until its lower end engages the broken end of rod A. The inclined lip 3 20 of the socket, engaging the end of rod, centers the rod with respect to the socket and directs it into the opening thereof between the toothed inner surfaces of the jaw 10 and slip 15, the slip 15 riding up along the guide 25 plate 11 until it is spaced from the jaw 10 a distance equal to or slightly greater than the diameter of the rod A. The slip 15, by its own weight, settles down as far as the rod will permit it and then when a pull is 30 exerted upon the socket and the weight of the lost section of the string of rods is imposed thereon, the hold upon the rod between the slip 15 and the jaw 10 is greatly increased and is made more positive by the 35 embedding of the teeth of the jaw and slip into the sides of the rod. Furthermore, the peculiar shape of the teeth which, as will be noted in Fig. 3, is straight on the upper sides and inclined on the lower, greatly enhances the security of the hold.

The bore 8 of the cap 5 is provided for the purpose of allowing the fluid within the tubing to escape through the barrel, so as not to retard the descent of the socket. 45 Upon withdrawing the socket, with the lost string of rods, from the well tubing, the socket may be lowered with respect to the broken rod sufficiently to break its hold upon the rod, and the slip 15 may be held 50 suspended by means of the stud 16 to prevent its taking hold again upon the rod while the socket is withdrawn endwise from the rod; and should the broken end of the rod have been inserted far enough into the 55 socket to engage firmly with the cap 5 so that this relative movement between the parts would be impossible, then the cap 5 may be unscrewed enough to loosen the parts after which the disengagement of the socket 60 from the rod may be easily accomplished.

Throughout the thickened lower end portion of the plate 11, the slot 17 is enlarged laterally along its outer side to correspond in width to and, in effect, to constitute a 65 continuation of the slot 19 of the barrel 1.

This is so the pin 16 may descend to the bottom of the slot, yet be short enough not to protrude when in its top position beyond the periphery of the barrel.

Having thus described my invention, 70 what I claim is:

1. A slip socket comprising, in combination, a cylindrical barrel, a fixed jaw secured within the barrel along one side thereof, a guide plate secured within the barrel in opposed relation to the fixed jaw, the guide plate having a portion that is inclined downwardly and inwardly toward the jaw, a slip having a tapered portion cooperating with the inclined portion of the guide plate and provided with means interlocking with a slot in the guide plate whereby the slip is retained against dislodgment from said plate. 75

2. A slip socket comprising, in combination, a supporting element, a barrel secured to said element and depending therefrom, a fixed jaw and a guide plate supported in opposed relation to each other inside the barrel and clamped between a part thereof and the aforesaid supporting element, the guide plate having a part inclined downwardly and inwardly toward the jaw, a slip cooperating with the inclined part of the guide plate, and means carried by the slip and interlocking with the guide plate to prevent 90 dislodgment of the slip. 85

3. A slip socket comprising, in combination, a supporting element, a barrel secured to said element and depending therefrom, the barrel having an internal shoulder adjacent its lower end, a jaw and a guide plate arranged in opposed relation to each other inside the barrel and clamped between the shoulder thereof and the aforesaid supporting element, the guide plate having a downwardly and inwardly inclined part, a slip cooperating with such inclined part, the guide plate having a longitudinal slot that is enlarged at its upper end adjacent the aforesaid supporting element, the barrel 100 having a slot registering with but wider than the slot of the guide plate, a stud projecting from the slip through the slot of the guide plate and having a head occupying the slot of the barrel, the head of the stud being of greater transverse dimension than the slot of the guide except where said slot is enlarged at its upper end, the supporting element being retractable from within the barrel but serving when in normal relation 105 thereto to prevent the slip from being elevated sufficiently to permit the head of the stud to pass through the enlarged upper end of the first mentioned slot. 110

4. A slip socket comprising, in combination, a supporting element, a casing secured to said element and depending therefrom, said casing having on its interior along one side, a fixed jaw, the interior surface of the casing opposed to said jaw being inclined 115 120 125

downwardly and inwardly, a slip for cooperation with the inclined surface of the casing and having a part interlocking with the casing for retaining the slip against dislodgment, the supporting element when in normal relation to the casing preventing disengagement of said interlocking parts but upon retraction from the casing permitting said interlocking parts to be disengaged

10 from each other.

5. A slip socket comprising, in combination, a cylindrical barrel having an internal shoulder at its lower end and which is internally threaded at its upper end, a cap for application to the upper end of the barrel and having a threaded extension that is screwed into the barrel, a fixed jaw on the interior of the barrel, the same having a ledge engaging the shoulder of the barrel

20 while its upper end is engaged by the aforesaid cap, a guide plate supported on the interior of the barrel opposite the fixed jaw,

said plate having a ledge engaging the shoulder of the barrel while its opposite end is engaged by the cap, means attaching the 25 fixed jaw and guide plate to the barrel, the guide plate having a portion of its inner surface inclined downwardly and inwardly, a slip designed to cooperate with the inclined portion of the guide plate, the guide 30 plate having a slot extending downwardly from its upper end, the barrel having a slot in register with but somewhat wider than the slot of the guide plate, a stud carried by the slip and extending through the slot of the 35 guide plate and terminating at its outer end in a head which occupies the slot of the barrel, the mouth of the barrel and the adjacent ends of the jaw and guide plate being inclined upwardly and inwardly.

40 In testimony whereof, I hereunto affix my signature.

ERNEST J. SHAFFER.
